Specification for Design.

Patented, Feb. 13, 1917.

Application filed September 23, 1916. Serial No. 121,889. Term of patent 3½ years.

To all whom it may concern:

Be it known that I, EUGENE IRVING HANSON, a citizen of the United States of America, and a resident of New Rochelle, in the county of Westchester, State of New York, have invented a new, original, and ornamental Design for a Textile Fabric, of which the following is a specification, reference being had to the accompanying drawing, showing my design.

The drawing shows a face view of a portion of fabric bearing my design.

The stripes a, b, c and d composing my design are separated or defined not by straight lines, but by irregular or wavy lines whereby the monotonous continuity of the stripes is broken and a soft draped effect is imparted to the fabric bearing my design.

The design is intended to be repeated on the fabric.

I claim:—

The design for a textile fabric as shown and described.

E. IRVING HANSON.
